UNITED STATES PATENT OFFICE.

WILLIAM PAINTER, OF BALTIMORE, MARYLAND.

LAMP-BURNER AND WICK THEREFOR.

SPECIFICATION forming part of Letters Patent No. 247,270, dated September 20, 1881.

Application filed May 9, 1881. (Model.)

To all whom it may concern:

Be it known that I, WILLIAM PAINTER, of Baltimore city, State of Maryland, have invented certain new and useful Improvements 5 in Lamp-Burners and Wicks Therefor; and I hereby declare the same to be fully, clearly, and exactly described as follows, reference being had to the accompanying drawings, in which—

- 10 Figure 1 is a central vertical sectional view of the device. Fig. 2 is a horizontal sectional view of the wick-tube, its inclosing-sleeve, and the partition-plate. Fig. 3 is a plan view of the device for joining the ends of the wick. Fig. 15 4 is a side elevation of the wick-tube, sleeve, and hook. Fig. 5 is a similar view at right angles to the last. Fig. 6 is an elevation of the partition-plate; and Figs. 7, 8, 9, and 10 are central sectional views of modified forms of the 20 device.

My invention embraces a new form of burner for lamps and a new mode of operating the wick. It is designed to overcome the objections incident to burners of ordinary kinds, and 25 attains valuable results not hitherto possible.

In all the common or heretofore known forms of burners the charring of the wick necessitated its constant trimming, the burner would smoke when the wick was turned too high, the flame 30 was generally very uneven, and the chimney, due to unequal heating, was apt to crack.

I have produced a lamp-burner and a wick especially adapted thereto whereby these and other well-known difficulties are wholly overcome and further advantages secured without 35 materially increasing the cost.

In the burner about to be described the wick requires no trimming, is utilized throughout its entire length, is automatically moved forward, 40 exposing a new burning-point every time the burner is lighted, does not become shorter by use, and a brilliant symmetrical flame of maximum size is always attainable without the exercise of care or skill. Furthermore, the burner 45 is of such construction that smoking is impossible, as the wick cannot be raised too high, and in the necessary forward movement of the wick it is drawn, not pushed, through the wick-tube, obviating the possibility of jamming. 50 The wick, moreover, cannot be drawn down into the lamp, and liability of explosion is thereby diminished. As incident to these advan-

tages the labor of cleaning the burner and chimney is greatly lessened, the chimney is less liable to be broken by uneven heating, the 5 flame remains full and brilliant as long as the oil lasts, the combustion is more perfect than in the ordinary burner, and there is little or no offensive odor.

My invention consists, broadly, first, in a 60 burner having a wick-tube adapted to receive a double thickness of the wick and project it, in the form of an abrupt loop, to a fixed and definite maximum distance above the tube, the said loop being the burning-point, in combination with a wick-moving mechanism; second, in a burner, having a wick-tube provided with a partition-plate for sustaining the loop of the wick, in combination with means for changing the burning-point; third, in a burner 65 having a wick-tube adapted, as described, to project and sustain an abrupt loop of the wick, and provided with mechanism whereby the wick is automatically moved forward, presenting a new burning-point every time the burner 70 is lighted; fourth, in so constructing the wick-tube and arranging the wick as to afford continually an ample supply of oil to the flame through both branches of the wick, whereby the destructive burning of the wick is prevented; fifth, in certain specific features of 75 construction; and, sixth, in an endless lateral-burning wick or its equivalent, as herein described, adapted to the said burner.

In the drawings, A is the cone, B the air-distributing plate, and C the screw-piece for attachment to the lamp, all of ordinary form.

E is the wick-tube, having lateral grooves e, in which slide the projections o of the partition-plate F. The grooves terminate near the 90 bottom of the wick-tube, as shown in Fig. 5, forming shoulders upon which the projections o rest, determining the distance to which the partition-plate, and consequently the loop of the wick, shall project above the tube. The 95 top of the partition-plate F is folded over, as at f, forming a smooth edge, over which the wick is drawn.

D is a sleeve inclosing and sliding upon the wick-tube, and provided with grooves d, which 100 register with similar ones on the tube E. To the sleeve D is pivoted through its lateral arms n a hook, G, which is provided with spurs m, that enter slots b in the wick-tube and

engage with the wick. The hook G is curved in the arc of a circle about its pivots, and has a number of perforations, g, with which the teeth of the wheel H engage.

5 The wick I may be woven in the form of an endless band, or else may be, and by preference is, formed from a piece of ordinary wicking by uniting the ends in any convenient way. A simple device for this purpose is shown in o Fig. 3, and consists of a narrow plate, J, of sheet metal, having tangs j. The ends of the wick are made to slightly overlap, as shown at i, Fig. 1. The tangs are bent at right angles to the plate J, thrust through the parts 5 of the wick on either side of the joint, and bent over or clinched on the opposite side. The end tangs are folded over the edges of the wick. The wick-tube E is extended upward at either side, forming semicircular ears l l, that inclose o and support the sides of the projecting loop and exclude the flame from the edges of the wick.

10 In operation the wick is inserted by thrusting a loop of the same downward through the wick-tube by means of the plate F, which is made long enough to cause the wick to pass out at the bottom of the tube, when the projecting part may be drawn down until the wick lies closely over the folded end of the plate 15 and between the ears l l, as shown in Figs. 1 and 4. Upon turning the wheel H in the direction of the arrow by means of an ordinary button on its shaft, the hook G is tilted upward until the spurs m are withdrawn from the wick and its upper edge comes in contact with the sleeve D. Further upward rotation of the hook being thus prevented, a continued movement of the wheel causes the sleeve D to slide upward, inclosing the projecting loop of the wick, 20 regulating the flame or diminishing it to such a degree as to be readily extinguished. When the burner is to be relighted the wheel H is turned in the opposite direction, tilting the hook downward, and causing its spurs to enter the slots and engage with the wick. When the spurs have entered the wick as far as they will go further motion of the wheel causes the hook, and with it the sleeve, to descend, drawing the wick over the top of the plate F, bringing a new burning-point into position, and at 25 the same time exposing the wick for relighting. In this way the wick is gradually and automatically fed around, never burning twice in the same place until it has completed its circuit.

30 The wick-moving mechanism described is in its action similar to the four-motion feed common in sewing-machines, and effects the necessary forward movement of the wick without materially disturbing or roughening its surface. Moreover, the feed is only possible in one direction, so that the wick is constantly advanced, but cannot be retracted. Inasmuch as the maximum exposed or burning portion 35 of the wick is determined and cannot be exceeded, the burner will not smoke, and, as the

portion referred to is always of uniform shape, the flame is necessarily symmetrical in form.

One of the salient features of my invention consists in the lateral-burning wick fed by the 70 immersion of both its branches in the oil, the tube being arranged to conduct them into the reservoir. A most important result is thereby attained. The oil is fed to the flame from both directions, and so liberally that the wick is 75 kept comparatively cool and its burning almost entirely prevented. This result is conducted to by the constant contact of the burning portion of the wick with the rounded end of the partition-plate, which carries off a considerable 80 portion of the heat, and the burner is so constructed that the flame may be regulated and the wick fed forward without at any time separating it from the partition-plate or loop-sustaining device. The wick is made to project from the inclosing-tube in the form of an abrupt loop or curve, in order to expose a substantially vertical burning-surface on either side—a feature of great importance, as it permits an upward vertical draft to the flame 85 much in the same manner as in an ordinary end-burning wick.

90 The limiting of the exposed or burning portion of the wick secures a peculiar advantage over all forms of burners heretofore known, 95 in that the wick can at once be exposed to its maximum on lighting the burner, and this exposure, while being the maximum, is not sufficient to permit it to smoke, whereby no necessity arises for regulating the flame after lighting, as is the case with ordinary burners.

95 As the result of the means I employ for preventing the destructive burning of the wick, it is found, in practice, to be charred to such a slight degree that it may be fed around and 100 be used a number of times, if desired, and when it finally becomes somewhat roughened, due to the burning through of the outermost strands, it may be reversed, so as to bring its other face outward and its use continued.

105 An especial advantage attending the use of an endless lateral-burning wick is that it does not become shortened by use, and hence always reaches to the bottom of the reservoir. Even when the oil is quite low a flame of large size 110 is produced, resulting from the ample supply of oil by both branches of the wick.

115 While the foregoing is a description of what I consider the best form of burners and wick embodying my invention, several modifications 120 of them differing from those already described in structure but not in principle may well be mentioned.

125 Instead of the removable partition-plate F, I may employ a fixed or removable pin connecting the ears l l for sustaining the loop, or in some cases the partition-plate may be made integral with the wick-tube, or the latter may consist of two tubes placed nearly or quite in contact. The removable partition-plate may 130 be inserted from below instead of from above; but the construction and arrangement first de-

scribed are obviously preferable, by reason of their simplicity and the facility afforded for inserting the wick.

One of the important features of my invention, consisting, as it does, in feeding the exposed portion of a lateral-burning wick by the capillarity of both its branches, it is clear that the ends of the wick need not of necessity be joined; nor need both ends or either of them be actually immersed in the oil, as a permanent wick attached to the lower end of the wick-tube may be used, for example, to feed the movable wick. Such a modification is shown in Fig. 7, the permanent wick I' being attached to the lower end of the wick-tube, the doubled or looped wick having its ends disconnected.

As a substitute for the hook G for feeding the wick, I may use the device shown in Fig. 8, in which p are tangs, either fixed or pivoted to the outer sleeve, which in this case is stationary, and project inward and downward through slots in the inner movable wick-tube, E. This latter tube is raised or lowered to regulate or extinguish the flame by the wheel P, its downward movement being limited by a suitable stop. As the wick-tube is raised, and with it the wick, in lighting the burner, the tangs catch in the wick and cause it to be drawn over the end of the partition-plate, as will be readily understood.

Another form of automatic-feeding device is shown in Fig. 10, depending for its operation upon the fact that the chimney is necessarily removed to light the burner. In this case a lever, s, works through a slot in the plate B, and is pivoted at t to a spring, S, attached to the plate B on the opposite side of the wick-tube. On the lower end of the lever are spurs s', that engage with the wick and draw it down. When the chimney is removed to light the burner the spring S lifts this lever into the position shown in the drawings, and when the chimney is replaced the lever at first tilts downward, causing its spurs to engage with the wick. As the chimney is pressed down into position on the plate B the lever moves bodily downward, thus giving a forward movement to the wick. In this form of burner the flame is regulated independently by a sliding sleeve and a ratchet-wheel, as shown.

Other forms of devices for moving the wick forward automatically, in the sense that they operate incidentally upon the performance of some other act of comparatively frequent occurrence in the use of the burner, will suggest themselves. For instance, the act of screwing the burner upon the lamp may be made, through suitable mechanism, to move forward the wick and bring a new burning-point into position. I find, however, that the conjoint action of the flame-regulating and wick-moving devices as first described gives the best results.

Now, while it is desirable that the construction and operation of the burner be such that the wick is automatically moved forward dur-

ing some operation preliminary to lighting it, in order to prevent the wick from being burned too long in one position, and thus destroyed from neglect, it is clear that the wick-moving mechanism may be independent, instead of automatic, the burner still retaining most of the essential features of the invention. One form of device of this kind is shown in Fig. 9, in which Q is a wheel for drawing the wick over the partition-plate to expose a new burning-point, and P another wheel for operating the sliding sleeve D to regulate the flame. This form of the device, however, while embodying many of the features of my invention, does not, as shown, retain one important one—namely, that of determining the distance to which the wick may possibly be raised, as by the reverse rotation of the wheel Q the loop of the wick would be lifted. It is obvious however, that means for preventing such reverse rotation might be added, such as a pawl engaging with the teeth of the wheel.

Other forms of devices, wherein the forward movement of the wick depends upon volition to that end on the part of the user of the burner, will suggest themselves. I may also say that other forms of wick-moving and flame-regulating devices are obvious, and that the details of construction and arrangement may be much varied while still conforming to the essential features; but the form first shown and described is considered the best embodiment of the invention. I therefore desire it to be understood that I do not confine myself to any precise construction or arrangement of the various parts of the burner.

I am aware of British Patent No. 2,523 of 1861, and without going to the extent of saying that the device therein shown is wholly inoperative and impracticable, I will say that it is open to the very objections that it is the design of my invention to obviate. The patent referred to shows a wick arranged to burn on its side. The wick-tube is bent in the form of an arc, with the upper portion cut away to expose the wick. As a result, the walls of the wick-tube contiguous to the burning-point of the wick on either side are not substantially parallel, as in my burner, and the currents of air meet the flame at an angle instead of vertically; but a single branch of the wick is immersible in the oil, and it is therefore liable to be quickly burned in two—a fact which the inventor evidently recognized, as he describes his wick as provided with a woven-wire backing to prevent its complete severance. Moreover, in regulating the flame the burning portion of the wick is raised and separated from the supporting parts, and is thus still more exposed to destructive burning. The exposure of the wick is not limited; hence the burner would as readily smoke as an ordinary one, and the wick constantly grows shorter by use. In addition to these grave defects, it lacks the important feature of the automatic feeding of the wick, and obviously many others of value.

characterizing my invention. In a word, the burner shown in the British patent referred to has nothing in common with my invention save the single feature of burning the wick on its side, and that I do not claim.

I am also aware that pieces of asbestos or similar material have been attached to the ends of ordinary wicks by means of tanged clasps; but the clasps were of such proportions and construction as to render them wholly unapplicable to the use to which I apply the clasps hereinbefore described. I do not, however, claim, broadly, a tanged clasp; but

What I do claim as structurally and functionally new is—

1. In a lamp-burner, a wick-tube adapted, as described, to receive a double thickness of wick and project it in the form of an abrupt loop, and provided with means for moving the wick and for sustaining the said loop at a fixed and definite maximum distance above the tube, whereby the flame is limited and smoking prevented, substantially as described.

2. In a lamp-burner, a wick-tube adapted to receive a double wick and having sides substantially parallel throughout their length, whereby the exposed loop or burning-point is caused to project abruptly from the inclosing-tube, so that the flame shall receive the air-currents in a substantially vertical direction, in combination with mechanism for moving the wick, substantially as described.

3. In a lamp-burner, a wick-tube adapted to receive a loop or double thickness of wick, in combination with mechanism for automatically moving the wick forward, whereby a new burning-point is brought into position, substantially as described.

4. In a lamp-burner, the combination of a wick-inclosing tube or tubes, a doubled or looped wick, a wick-supporting device, and mechanism for automatically moving the wick forward, whereby a new burning-point is brought into position, substantially as described.

5. In a lamp-burner adapted for a lateral-burning wick, the combination of the flame-regulating device with the wick-moving mechanism, whereby the movement of the flame-regulating device for alternately extinguishing and relighting the burner shall automatically cause a forward movement of the wick, substantially as described.

6. In a lamp-burner adapted for a lateral-burning wick, the sliding sleeve for regulating the flame, carrying the wick-moving mechanism, the parts being so arranged that the sleeve may be moved upward to reduce or extinguish the flame, and in its descent move the wick forward, bringing a new burning-point into position, and at the same time exposing the wick for lighting, substantially as described.

7. In a burner adapted for a lateral-burning wick, a wick-moving mechanism arranged intermediate the propelling-shaft and flame-regulating device, whereby the engagement or dis-

engagement of said wick-moving mechanism with the wick is effected before the flame-regulating device is moved in either direction, and the roughening of the surface of the wick is prevented, substantially as described.

8. In a lamp-burner adapted for a lateral-burning wick, a flame-regulating device adapted to partially or wholly inclose the projecting loop or burning portion of the wick and movable with respect to the loop-sustaining device, whereby the flame may be regulated without raising or separating the wick from the loop-sustaining device, substantially as described.

9. In a lamp-burner adapted for a lateral-burning wick, the combination of the partition-plate for sustaining the loop in a fixed relation to the inclosing-tube, and the sliding sleeve for regulating the flame, the parts being so arranged that the exposed or burning portion of the wick shall be limited in extent to prevent smoking, and the regulation or extinguishment of the flame effected, substantially as described.

10. In a lamp-burner adapted for a lateral-burning wick, a tube or tubes arranged to conduct both branches of the doubled wick through the base of the burner and into the oil-reservoir, in combination with means for changing the burning-point of the wick, whereby both of its branches may be utilized in conducting oil to the flame and the wick burned progressively, substantially as described.

11. In a lamp-burner adapted for a lateral-burning wick, a wick-tube having sides substantially parallel throughout their length, a partition-plate, and mechanism for drawing the wick longitudinally over the end of said plate, substantially as described.

12. In a lamp-burner adapted for a lateral-burning wick, a single wick-inclosing tube having sides substantially parallel throughout their entire length, in combination with a partition-plate or loop-sustaining device, and means for automatically moving the wick, substantially as described.

13. In a lamp-burner adapted for a lateral-burning wick, the combination of the wick-tube, wick-moving mechanism, and removable partition-plate, substantially as described.

14. In a lamp-burner adapted for a lateral-burning wick, a removable partition-plate and means for sustaining it centrally in the wick-tube, substantially as described.

15. In a lamp-burner adapted for a lateral-burning wick, a wick tube or tubes inclosing a double thickness of wick and a sliding sleeve arranged to surround the projecting loop for regulating the flame, substantially as described.

16. In a lamp-burner adapted for a lateral-burning wick, the sliding sleeve carrying the pivoted hook, actuated by the ratchet-wheel, substantially as described.

17. In a lamp-burner adapted for a lateral-burning wick, the combination of the wick-inclosing and loop-sustaining parts with reciprocating wick-moving mechanism, whereby a lim-

ited forward movement of the wick is effected, substantially as described.

18. In a lamp-burner adapted for a lateral-burning wick, a wick-tube arranged to conduct both branches of the wick into the oil-reservoir, and mechanism adapted to feed the wick in one direction only, whereby a new burning-point is brought into position and excessive charring prevented, substantially as described.

19. In a lamp-burner adapted for a lateral-burning wick, the combination of the wick-tube, the inclosing-sleeve, and removable partition-plate, substantially as described.

20. In a lamp-burner adapted for a lateral-burning wick, the wick-tube having sides substantially parallel throughout their entire length and side ears projecting above the end of said tube for sustaining and protecting the edges of the wick at the loop or burning-point, substantially as described.

21. In a lamp-burner adapted for a lateral-burning wick, wick-moving mechanism arranged to be operated by the lamp-chimney, whereby the act of placing the chimney on the burner shall cause the forward movement of the wick, substantially as described.

22. In a lamp-burner, an endless lateral-burning wick, in combination with means for projecting a loop of the same from its inclosing-tube and for changing the position of said loop, substantially as described.

23. An endless lateral-burning wick consisting of a strip of ordinary wicking having its ends lapped and joined by means of a tanged clasp, substantially as described.
